REMOTE CONTROL RECEIVER

Leslie F. Curtis, Great Neck, N. Y., assignor to
Hazelton Corporation, a corporation of Delaware

Application December 31, 1938, Serial No. 248,708

12 Claims. (Cl. 250—20)

This invention relates generally to remotely controllable radio receivers and particularly to receivers comprising a remote control system not involving the use of additional control wires between the remote control unit and the receiver. While the invention is of general application, it is of particular utility in providing an on-off control in a receiver of the above-mentioned type.

It is frequently desirable to effect a control of a radio receiver from a point remote from the receiver. For instance, it may be desirable to place the bulky parts of the receiver at some convenient part of the room or at some position to procure the best acoustical effect and to control the receiver by means of a compact control unit from a remote point. Furthermore, it may be desirable to move the control unit from one part of the house to another. In such receivers, it is desirable to provide an on-off control at the remote unit which is effective, upon operation, to generate a control signal for only a short period to effect the desired control operation at the receiver; for instance, to turn on the receiver, and thereafter condition the system to effect a different type of control operation when next operated, for instance, to turn off the receiver, and to repeat this cycle of operations in sequence. It is furthermore desirable to provide a single control for supplying power to the control unit and to the receiver. Also, it may be desirable in some instances to combine this single control with the conventional manual volume control of the receiver.

In some receivers of the prior art, a continuous control signal from the remote control unit has been utilized to maintain the receiving unit in an operative condition. This is undesirable both for the reason that additional power is required and for the reason that signal reproduction may be interfered with by the control signal. In other arrangements of the prior art for providing an on-off operation for remotely controlled radio receivers, it has been necessary manually to control the length of time for which a control signal is generated by manually effecting an operation to discontinue the control signal. Furthermore, in some remote control arrangements it has been necessary to use a separate manually controlled switch for energizing the control unit in order thereafter to operate the "off-on" switch at the receiver.

On the other hand, it is desirable, in remote-control arrangements of the type under consideration, to be able to turn off the receiver from

the remote control station by means of a control arrangement which maintains the control signal only for a sufficient length of time to disconnect the power from the receiver proper and which thereafter is itself disconnected from its own source of power, thereby avoiding the necessity for stand-by power.

It is an object of the present invention, therefore, to provide a wave-signal receiver including a remote control system which is effective to provide a control signal for a short time only and thereafter condition the control arrangement for the next operation in the control cycle.

It is another object of the invention to provide a remote control for a radio receiver, including a remote off-on control, in which the control signal is generated for a short time only and in which no stand-by power is required.

In accordance with the invention, there is provided in a modulated-carrier signal receiver a remote-control apparatus comprising a control generator for providing a control signal to effect the control operations at the receiver. The remote control apparatus includes control means adapted to be operated to a plurality of positions in a predetermined sequence together with a plurality of means each responsive to operation of said control means to a predetermined one of said positions and adapted to condition said generator to provide an output of a different characteristic. A time-delay device is associated with the plural means for effecting operation of the generator for each of the positions of the control means for a limited time only and thereafter for conditioning the generator for operation with another predetermined one of said characteristics upon operation of the control means to the next position in the sequence.

In the preferred embodiment of the invention, the generator is a high-frequency oscillator comprising a plurality of fixed-tuned condensers adapted to be selectively included in the circuit of the oscillator, thereby to provide a control signal of a different frequency for each of the positions of the control means. Also in the preferred embodiment of the invention, the remote control arrangement is utilized as an off-on switch for the radio receiver and the control means is adapted to be operated alternately to each of two different positions, the oscillator being effective in one of the positions of the control means to provide a control signal effective to connect the receiver proper to its power supply source and being effective in the other of the positions of the

control means to disconnect the receiver from its power supply source.

For a better understanding of the invention, together with other and further objects thereof, 5 reference is had to the following specification taken in connection with the accompanying drawing, and its scope will be pointed out in the appended claims.

The single figure of the drawing is a circuit 10 diagram, partly schematic, of a complete superheterodyne receiver embodying the invention.

Referring now more particularly to the drawing, there is shown schematically a superheterodyne receiver including a remote carrier-frequency section 10 and a local modulation-frequency section 11. Considering first the essential elements of the receiver per se, it comprises, in general, an antenna ground circuit 12, 13 coupled to a power transmission line 14 through 15 an impedance-matching device 9 and a convenience outlet and plug 15; a radio-frequency selector and amplifier 16 having its input circuit coupled to power supply line 14 through a convenience outlet and plug 15 and an impedance-matching device 17 and its output circuit connected to a tunable frequency changer or oscillator-modulator 18, the output circuit of which is coupled, in turn, to the input circuit of an intermediate-frequency selector and amplifier 19. 20 The intermediate-frequency output circuit of amplifier 19 is coupled through an impedance-matching device 20, conductors 21, switch 65, and convenience outlet and plug 15 to the power line 14, in order that the intermediate-frequency signals 25 may be transmitted to the modulation-frequency section 11 of the receiver over the power line 14.

The modulation-frequency section includes a second intermediate-frequency amplifier 23, 40 coupled through an impedance-matching device 24 and convenience outlet and plug 15 to the power line 14. Connected in cascade to the output circuit of intermediate-frequency amplifier 23, in the order named, are a signal detector 45 23a, an audio-frequency amplifier 25, and a sound-reproducing device 26.

An automatic amplification control or AVC bias is derived in section 10 from an AVC supply unit 27, coupled to amplifier 19, and is supplied 50 over conductor 28 to the control grids of one or more of the tubes of radio-frequency amplifier 16, oscillator-modulator 18, and intermediate-frequency amplifier 19 to maintain the input to detector 23a within a relatively narrow range for a wide range of received signal amplitudes. 55 A power supply unit 30 is provided for section 10 of the receiver and is connected to the power line 14 to provide operating potentials for the tubes of section 10 over conductor 31 in a conventional manner. A power supply unit 33 is similarly provided for section 11 of the receiver and, 60 when coupled to the power line 14 through a control relay described hereinafter, provides operating potentials for the tubes of section 11 over a conductor 35 in a conventional manner.

Generally speaking, the operation of the receiver just described is well understood in the art and a detailed description thereof is unnecessary. In brief, however, signals intercepted by 70 the antenna 12, 13 are transmitted by impedance-matching device 9, power supply line 14, and impedance-matching device 17 to radio-frequency amplifier 16, wherein they are amplified and translated to the tunable frequency changer 75 18 for conversion to intermediate-frequency sig-

nals in a well known manner. The intermediate-frequency signals are selected and amplified in intermediate-frequency amplifier 19 and translated through impedance-matching device 20, conductors 21, power supply line 14, and impedance-matching device 24 to the second intermediate-frequency amplifier 23 for further selection and amplification. The intermediate-frequency output of amplifier 23 is passed to detector 23a wherein the audio frequencies of modulation are derived. The audio-frequency signal is further amplified in amplifier 25 and supplied in the usual manner to loudspeaker 26 for reproduction. The unidirectional output of the 10 AVC supply unit 27, applied by way of connection 28 to the control grids of one or more of the tubes of radio-frequency amplifier 16, oscillator 18, and intermediate-frequency amplifier 19, 15 maintains the amplitude of the signal input to detector 23a within a relatively narrow range 20 for a wide range of received signals.

It is seen that the control section 10 of the receiver comprises all the conventional control elements of a receiver of the superheterodyne type and the remaining elements of a conventional superheterodyne receiver are comprised within the section 11. A receiver of this type is described and claimed in the copending application, Serial Number 212,902, filed June 10, 1938, on the application of L. M. Hershey. In the description which has been given above, elements which are similar to those of the above-mentioned copending application have been given identical reference numerals.

In order that the power supply unit 33 of section 11 may be connected to power line 14 through the local control relay by means of an operation effected at control unit 10, there is provided in accordance with the present invention an off-on signal generator 38 comprising an oscillator for generating a signal which is effective to energize a control relay 39 of section 11 having contacts 34 included in the circuit of power supply unit 33. It will be understood that relay 39 may be of a conventional type, the operation of which is well understood in the art, and is effective when energized by means of a given signal to close its contacts 34 and effective when energized by means of a different predetermined signal to open its contacts 34. The generator 38 comprises a vacuum tube 60 having a frequency-determining circuit including a condenser 63 and an inductance 61 in its output circuit inductively coupled to an inductance 62 in the input circuit. In order to condition the generator to provide control signals of a different frequency there is provided a tuning condenser 64 adapted to be selectively connected in circuit with condenser 63. A manual control arrangement is provided for generator 38 including a double-throw switch 66. A switch 65, included in the power supply circuit to the power supply unit 30 is connected for unicontrol with switch 66 by means of unicontrol mechanism 67 and may comprise there-with a double-pole double-throw switch.

In order that the control signal of oscillator 38 will be supplied to power line 14 for only a short time, upon the operation of control switches 65, 66, there is provided a thermostatic time-delay relay 68 operated by means of a heater 69 connected to power supply 30. The relay 68 is effective in its two positions to condition the oscillator 30 to provide control signals of different frequencies by the inclusion or exclusion of condenser 64 in the frequency-determining circuit 75

of the oscillator. Power for the operation of oscillator 38 is supplied from the power supply source 14 and time-delay relay 68 also provides an arrangement for disconnecting the filament circuit of vacuum tube 60 from the power-supply source after a predetermined length of time.

In considering the operation of the portion of the circuit constituting the present invention, it will be assumed that switch 65 is closed and that switch 66 and time-delay relay 68 are in the positions shown. It will be seen that, under these conditions, power is being supplied to power supply unit 30 and that heater 69 is energized to maintain the thermostatic time-delay relay 68 in the position shown. Under this condition, it is assumed that the receiver is in operation but that the filament circuit of tube 60 is open at the upper contact of switch 66 so that oscillator 38 is not in operation. If unicontrol arrangement 67 is then operated to its upper position to turn off the receiver, the oscillator 38 including tube 60 generates a frequency which is dependent upon the value of condenser 63, since the circuit of condenser 64 is open at the lower contact of relay 68, and which is effective to operate relay 39 to open its contacts 34 to deenergize the receiver section 11. However, at the instant the unicontrol arrangement 67 is operated to its upper position, power supply 30 is disconnected from power line 14 by switch 65, thereby deenergizing heater 69. After a length of time, during which the thermostatic element of relay 68 cools, relay 68 operates to open its upper contacts to disconnect the filament circuit of vacuum tube 60 from power supply line 14, thereby effectively discontinuing the control signal which is being generated. Relay 68 is also effective upon operation at this time to close its lower contacts to connect condenser 64 effectively in parallel with condenser 63 in the frequency-determining circuit of oscillator 38. If now unicontrol mechanism 67 is operated to throw switches 65 and 66 to their lower positions, the filament circuit of tube 60 is again energized through the lower contacts of switch 66 and relay 68 and the oscillator 38 generates a control signal of a frequency dependent on the value of condensers 63 and 64 in parallel, this control signal being effective to turn on the receiver section 11 by the operation of relay 39 to close its contacts 34. Also, upon operation of unicontrol mechanism 67, power is supplied to power supply unit 30, thereby energizing heater 69. Time-delay relay 68 operates after a time delay again to open its lower contacts to disconnect the filament of tube 60 from power line supply 14 and to disconnect condenser 64 from the frequency-determining circuit of the oscillator. The oscillator 38 is thus deenergized and conditioned so that, upon the next operation of unicontrol mechanism 67, a frequency is generated which is effective to operate the on-off signal-responsive relay 39 to turn off the receiver and this cycle of operations may be repeated as desired.

65 It will be seen that the circuit for energizing the filament of tube 60 through double-throw switch 66 and double-throw switch 68 is similar to a three-wire lighting circuit, well known in the art, by which a light can be switched on or off at either of two remotely spaced switches.

It will be understood that a manual volume control arrangement may be provided within the unit 10 and that switches 65 and 66 may be unicontrolled with the volume control mechanism.

70 Such a unicontrol mechanism is then effective

to provide "on-off" control near one of its limiting positions and to provide volume control over the major portion of its motion.

While there have been described what are at present considered the preferred embodiments of this invention, it will be obvious to those skilled in the art that various changes and modifications may be made therein without departing from this invention, and, therefore, it is aimed in the appended claims to cover all such changes and modifications as fall within the true spirit and scope of this invention.

What is claimed is:

1. In a modulated-carrier signal receiver, a remote-control apparatus comprising, an electrical generator for providing a control signal to effect control operations at said receiver, control means adapted to be operated to a plurality of positions in a predetermined sequence, means responsive to operation of said control means to each of said positions to condition said generator to provide a predetermined control signal, and means including a time-delay device for effecting operation of said generator for a limited time only upon operation of said control means to each of 15 said positions and thereafter conditioning said generator for operation upon adjustment of said control means to the next position in said sequence.

2. In a modulated-carrier signal receiver, a remote-control apparatus comprising, an electrical generator for providing a control signal to effect control operations at said receiver, control means adapted to be operated to a plurality of positions in a predetermined sequence, means responsive to operation of said control means to each of said positions to condition said generator to provide a control signal of a different characteristic, and means including a time-delay device electrically interlocked with said control 20 means for effecting operation of said generator for a limited time only upon operation of said control means to each of said positions and thereafter conditioning said generator to provide a control signal of another predetermined 25 characteristic upon operation of said control means to the next position in said sequence.

3. In a modulated-carrier signal receiver, a remote-control apparatus comprising, an electrical generator for providing a control signal 30 to effect control operations at said receiver, control means adapted to be operated to a plurality of positions in a predetermined sequence, means responsive to operation of said control means to each of said positions to condition said generator to provide a control signal of a different 35 characteristic, and means including a time-delay device for effecting operation of said generator for a limited time only upon operation of said control means to each of said positions and thereafter conditioning said generator to provide a control signal of another predetermined 40 characteristic upon operation of said control means to the next position in said sequence.

4. In a modulated-carrier signal receiver, a remote-control apparatus comprising, a high-frequency oscillator for providing a control signal to effect control operations at said receiver, control means adapted to be operated to a plurality of positions in a predetermined sequence, 50 means responsive to operation of said control means to each of said positions to condition said oscillator to provide a control signal of a different 55 characteristic, and means including a time-delay device for effecting operation of said generator for a limited time only upon operation of said control means to each of said positions and thereafter conditioning said generator to provide a control signal of another predetermined 60 characteristic upon operation of said control means to the next position in said sequence.

4. In a modulated-carrier signal receiver, a remote-control apparatus comprising, a high-frequency oscillator for providing a control signal to effect control operations at said receiver, control means adapted to be operated to a plurality of positions in a predetermined sequence, 70 means responsive to operation of said control means to each of said positions to condition said oscillator to provide a control signal of a different frequency characteristic, and means including a time-delay device for effecting opera- 75

- tion of said oscillator for a limited time only upon operation of said control means to each of said positions of said control means and thereafter conditioning said oscillator to provide a control signal of another predetermined frequency characteristic upon operation of said control means to the next position in said sequence.
5. In a modulated-carrier signal receiver, a remote-control apparatus comprising, a high-frequency oscillator for providing a control signal to effect control operations at said receiver, control means adapted to be operated to a plurality of positions in a predetermined sequence, a plurality of adjustably fixed tuning elements, certain of said elements being adapted to be inserted into the frequency-determining circuit of said oscillator by operation of said control means to a predetermined one of said positions to condition said oscillator to provide a control signal of a different frequency characteristic, and means including a time-delay device for effecting operation of said oscillator for a limited time only upon operation of said control means to each of said positions of said control means and thereafter conditioning said oscillator to provide a control signal of another predetermined characteristic upon operation of said control means to the next position in said sequence.
6. In a modulated-carrier signal receiver, a remote-control apparatus comprising, a high-frequency oscillator for providing a control signal to effect control operations at said receiver, control means adapted to be operated to a plurality of positions in a predetermined sequence, a plurality of fixed condensers, certain of said condensers being adapted to be inserted into the circuit of said oscillator by operation of said control means to a predetermined one of said positions to condition said oscillator to provide a control signal of a different frequency characteristic, and means including a time-delay device for effecting operation of said oscillator for a limited time only upon operation of said control means to each of said positions of said control means and thereafter conditioning said oscillator to provide a control signal of another predetermined frequency characteristic upon operation of said control means to the next position in said sequence.
7. In a modulated-carrier signal receiver, a remote-control apparatus comprising, an electrical generator for providing a control signal to effect control operations at said receiver, control means adapted to be operated alternately to each of two different positions, two means responsive to said control means in a predetermined one of said positions to condition said generator to provide a predetermined control signal, and means including a time-delay device for effecting operation of said generator for a limited time only upon operation of said control means to each of said positions and thereafter conditioning said generator for operation upon adjustment of said control means to its other position.
8. In a modulated-carrier signal receiver, a remote-control apparatus comprising, an electrical generator for providing a control signal to effect control operations at said receiver, control means adapted to be operated to a plurality of positions in a predetermined sequence, means responsive to the operation of said control means to each of said positions to condition said generator to provide a predetermined control signal, and means including a thermostatic time-delay device for effecting operation of said generator for a limited

time only upon operation of said control means to each of said positions of said control means and thereafter conditioning said generator for operation upon adjustment of said control means to the next position in said sequence.

9. In a modulated-carrier signal receiver, a remote-control apparatus comprising, an electrical generator for providing a control signal to effect control operations at said receiver, control means adapted to be operated to a plurality of positions in a predetermined sequence, means responsive to the operation of said control means to each of said positions to condition said generator to provide a predetermined control signal, a thermostatic time-delay device having a predetermined time delay upon energization and a predetermined time delay upon deenergization, and means including said time-delay device for effecting operation of said generator for a limited time only upon operation of said control means to each of said positions of said control means and thereafter conditioning said generator for operation upon adjustment of said control means to the next position in said sequence.

10. In a modulated-carrier signal receiver, a remote-control apparatus comprising, a remote unit including an electrical generator for providing a control signal to effect control operations at said receiver, means for coupling said remote unit to a source of power supply, control means adapted to be operated to a plurality of positions in a predetermined sequence, means responsive to operation of said control means to each of said positions to condition said generator to provide a predetermined control signal, a thermostatic time-delay device dependent upon connection to said power supply source for operation with a given time delay, and means comprising said time-delay device for effecting operation of said generator for said given time only for each of said positions of said control means and thereafter conditioning said generator for operation upon adjustment of said control means to the next position in said sequence.

11. In a modulated-carrier signal receiver, a remote-control apparatus comprising, a high-frequency oscillator including a vacuum tube for providing a control signal to effect control operations at said receiver, means for coupling said vacuum tube to a source of power supply, control means adapted to be operated to a plurality of positions in a predetermined sequence, means responsive to operation of said control means to each of said positions to condition said generator to provide a predetermined control signal, and means including a time-delay device for effectively disconnecting said first-mentioned means for effecting operation of said generator for a limited time only for each of said positions of said control means and thereafter conditioning said generator for operation upon adjustment of said control means to the next position in said sequence.

12. In a modulated-carrier signal receiver, a remote-control apparatus comprising, a high-frequency oscillator including a vacuum tube having a cathode for providing a control signal to effect control operations at said receiver, a cathode-heating circuit, means for operatively connecting said tube including said cathode-heating circuit to a source of power supply, control means adapted to be operated to a plurality of positions in a predetermined sequence, means responsive to the operation of said control means to each of said positions to condition said oscillator to

- provide a predetermined control signal, and means including a time-delay device for effectively disconnecting said cathode-heating circuit from said power supply thereby to effect operation of said generator for a limited time only for each of said positions of said control means, said

last-mentioned means being effective thereafter to condition said generator for operation upon adjustment of said control means to the next position in said sequence.
